United States Patent Office

Des. 185,356
Patented June 2, 1959

185,356

MOBILE SANITARY FOOD CARRIER

William H. Frick, Cleveland, Ohio

Application October 19, 1956, Serial No. 43,534

Term of patent 14 years

(Cl. D14—3)

The figure is a perspective view of a mobile sanitary food carrier, embodying my new design.

I claim:

The ornamental design for a mobile sanitary food carrier, as shown.
